TEACHING DEVICE DEMONSTRATING BI-NOMIAL DISTRIBUTION CURVES

Hyman Ruchlis, Brooklyn, N.Y., and Edmund C. Berkeley, Newtonville, Mass., assignors to Science Materials Center

Filed Aug. 25, 1961, Ser. No. 66,494

Term of patent 14 years

(Cl. D25—1)

Fig. 1.

Fig. 2.

FIG. 1 is a front elevational view of a teaching device demonstrating binomial distribution curves, showing our new design; and

FIG. 2 is a side elevational view thereof.

We claim:

The ornamental design for a teaching device demonstrating binomial distribution curves, substantially as shown.
